(57) **CLAIM**

The ornamental design for a eye wrinkle treatment pad, as shown and described.

DESCRIPTION

FIG. 1 is a perspective view of an eye wrinkle treatment pad, embodying our new design;

FIG. 2 is a rear elevational view thereof;

FIG. 3 is a left side elevational view thereof;

FIG. 4 is a top view thereof;

FIG. 5 is a right side elevational view thereof;

FIG. 6 is a bottom view thereof;

FIG. 7 is a front elevational view thereof;

FIG. 8 is a perspective view of an alternative embodiment of the eye wrinkle treatment pad design;

FIG. 9 is a rear elevational view thereof;

FIG. 10 is a left side elevational view thereof;

FIG. 11 is a top view thereof;

FIG. 12 is a right side elevational view thereof;

FIG. 13 is a bottom view thereof; and

FIG. 14 is a front elevational view thereof.

FIG. 15 is a perspective view of another alternative embodiment of the eye wrinkle treatment pad design;

FIG. 16 is a rear elevational view thereof;

FIG. 17 is a left side elevational view thereof;

FIG. 18 is a top view thereof;

FIG. 19 is a right side elevational view thereof;

FIG. 20 is a bottom view thereof; and,

FIG. 21 is a front elevational view thereof.
